UNITED STATES PATENT OFFICE.

SAMUEL H. BROWNING, OF ATLANTA, GEORGIA.

LOOP-WINDING MACHINE.

Application filed February 10, 1925. Serial No. 8,282.

Generically this invention relates to winding or reeling machines, but it more especially comprehends the type adaptable for winding loops, reeling wire, winding field 5 coils, transformer coils, and the like.

One object of this invention is to provide a winding machine embodying a novel type of rigid winding head bar graduated to facilitate an accurate set-up for length of loop 10 and designed to eliminate possible variations in loop lengths where a plurality of loops are wound at one setting.

Another object of this invention is to design a winding machine embodying a rigid 15 winding head bar provided with adjustable means for forming varied width loops, means for releasing the tension on the completed loop, and additional means instantly detachable to facilitate removal of the loop 20 from the winding pins.

Still another object of this invention is the provision of a machine of the above character embodying a clamping block means associated with the winding head bar for holding 25 the starting lead wires, eliminating any wastage of wire, and placing inside lead wire or wires in correct position for finished loop.

A further object of this invention is the provision of a winding machine of the above character embodying a system of gearing 30 interconnecting a low speed shaft carrying a winding head bar and a high speed shaft provided with novel clutch means for instantly starting or stopping the rotation of the said low speed or winding head bar shaft as desired.

Other objects of the invention are: to provide additional means attachable to the winding pin blocks or head bar for winding 35 odd shaped coils; reel means attachable to the drive or high speed shaft for facilitating the rapid winding of field coils and for transferring wire from large to small reels.

With these and other objects in view, which will become apparent as the description proceeds, the invention resides in the construction, combination and arrangement 45 of parts, hereinafter more fully described and claimed, and illustrated in the accompanying drawings, in which like characters of reference indicate like parts throughout the several figures, of which:

Fig. 1 is a perspective view of my improved loop winding machine;

Fig. 2 is a top plan view of Fig. 1 showing the gearing, clutch and brake structure with the winding head bar removed;

Fig. 3 is a top plan view of the winding head for initially shaping wires into loops; 60

Fig. 4 is a front elevation of winding head;

Fig. 5 is a right side elevation of winding head;

Fig. 6 is a top and front elevation of 65 trigger-block body;

Fig. 7 is a top and front elevation of the trigger removed from the body;

Fig. 8 is a top plan view of wire clamping trigger-block removed from winding head; 70

Fig. 9 is a left end elevation of Fig. 8; and

Fig. 10 is a right end elevation of Fig. 8.

Fig. 11 is a side elevation of the trigger block showing the trigger operatively positioned. 75

I am aware that there are many winding machines and varied types of winding heads in use, but these have proved unsatisfactory, in that, they were either not accurate 80 in the width or length of the loops, or the finished loop was difficult to remove, or the lead wires could not be expeditiously held in place, and it was to overcome the deficiencies of such devices and to provide a winding machine and winding head comprehending novel and improved features embodying means for perfectly controlling the device, rigid winding head bar, lead clamping trigger-block, variable speed shafts, and surplus power on winding head shaft through special gearing interconnecting the said shafts, and other features that will be more fully explained as the description proceeds, that I evolved the loop winding machine 95 forming the subject matter of this invention.

In the illustrated embodiment characterizing this invention there is shown a frame 1 formed with cross bars 2 adapted to support bearings 3 in which is journaled power shaft 4 carrying a plurality of ratioed pulleys 5, 6, and 7. The said frame 1 is formed with integral upper cross bars 8 adapted to support suitable bearings in which are mounted the power or high speed shaft 9, 100 intermediate or gearing shaft 10 and low speed or winding head shaft 11. Loosely mounted on the drive shaft 9 intermediate the bars 8 are the pulleys 12, 13, and 14, ratioed inversely to the lower pulleys 5, 6, 105 110

and 7, the outer face of the said pulley 14 is concaved as at 15 conforming in configuration to and adapted to contact with the beveled or cone-shaped surface 16 of the 5 clutch A when the latter is brought into operative position. The clutch A embodies the cone-shaped members 17 and 18 integrally connected by the hub 19 internally slotted as at 20 adapted to slidably receive 10 the feather key 21 suitably secured to the shaft 9 or formed integral therewith.

The outer surface 22 of cone member 18 is adapted to engage the inner surface of 15 brake drum 23 suitably secured to frame bar 8 when member 18 is moved to braking position. The hub 19 is centrally recessed as at 24 to receive the fingers of the U-shaped clutch fork 25 which is secured to a horizontal pin 25^a by means of set screws 25^b. The said pin passes through holes in the two lugs 25^c formed on horizontal plug member 25^d which connects the prime member 1 together at the top just under the hood. The right hand end of pin 25^a is beveled for 25 contact with the complementary beveled surface 25^e at the upper end of connecting rod 27, the lower end of said rod being hingedly connected to arm 28 secured to the inner end of pedal rod 29 journaled through the lower 30 extremity of frame 1 and provided at its outer end with pedal 30. Thus when stepping on pedal 30, the rod 27 is moved vertically contacting the bevel surfaces in a wedging action which forces the clutch fork 35 25 to the left bringing surface 16 of clutch A in contact with the cone pulley 14 to transmit driving power to shaft 9 and through the train of gears to rear shaft 11. The clutch fork 25 is connected intermediate its 40 length to frame 8 by coil spring 26 which normally holds surface 22 in contact with the inner surface of brake drum 23, which serves to lock the machine in normal position and prevents it from backing up and 45 slackening up on the wires which are being wound into a loop on the winding head.

One end of shaft 9 extends through the casing 31 to which may be secured a reeling attachment (not shown) for winding field 50 coils and for transferring wire from large to small reels and the like. Mounted on the other end of shaft 9 adjacent pulley 12 is the small gear 32 adapted to mesh with the large gear 33 secured to shaft 10, which also 55 carries adjacent gear 33 small gear 34 adapted to mesh with large gear 35 mounted on winding head shaft 11, one end of which extends through the casing 31 and beyond the frame member 8, and externally threaded 60 to engage the internally threaded hub member 36 of the winding head.

The outer end of hub 36 is apertured to receive the head bar 37 firmly secured therein by cap screw or pin 38 which passes 65 through said hub and head bar and which

also serves to secure slotted adjustable plate 39 carrying pin 40 to which the ends of the wires may be fastened when starting to wind a loop, in case the lead wire clamping trigger block hereinafter described is not employed. 70

The head bar 37 is formed with a longitudinal guide rib 41 adapted to engage a corresponding slot in the hub 36 and to act as a guide for all parts slidably carried by 75 said bar. Slidably mounted on the said head bar 37 on each side of the hub 36 are the winding pin blocks 42 provided with winding pins 43 threadedly or otherwise suitably secured therein and externally threaded to 80 engage the internally threaded adjustable nuts 44.

The trigger-block 45 embodies a pair of spaced circular plate members joined by an eccentric segmental hub section 46 and a trigger member 47 adapted for insertion between the plates and pivotedly mounted therebetween by a pin passing through apertures 48 in the plate members and 49 in the trigger 47. A compression spring 50' is 85 mounted on the pin 50 and adapted to seat against the trigger and the hub 46 to normally maintain the notch 51 in engagement with an annular groove formed in the pin 43 predeterminedly spaced from the adjustable nut 44. The said trigger-block 45 may be detached from the winding pin 43 by depressing the free end of trigger 47 disengaging the notch 51 from the groove. 90

The winding pin blocks 42 are provided 100 at their rear ends with projections 42' suitably secured thereto and on which are adapted to be fastened extension arms 52 with their upper ends apertured to receive extension pin blocks 53 secured thereto by nuts 105 54, the outer ends of blocks 53 carrying winding pins 43', adjusting nuts 44' and trigger blocks 45' exactly as heretofore described in connection with the pin blocks 42, these extensions being provided for use 110 where it is desired to wind odd shaped coils.

One side of the winding head bar 37 is graduated on each side of the hub 36, as at 115 55, so that the winding pin blocks 42 may be accurately adjusted to provide loops of varying lengths, and they are firmly secured on said bar 37 by clamping members 56 positioned adjacent said blocks and connected thereto by bolts 57 carried by said members 56 and adapted to threadedly engage the blocks 42, the said clamping members being secured to the bar 37 at any desired points by bolts 58.

In order to expedite the removal of the 120 finished loop 59 from the winding pins 43 it is advisable to have one of the pin blocks 42 independently adjustable with respect to its adjacent clamping or anchoring member 56 which is effected by substituting for the bolt 57, rod 60 having one end threadedly or 125 130

otherwise secured to block 42 slidably extending through clamping member 56 with its outer end pivotedly secured to cam lever 61 and carrying intermediate block 42 and 5 clamp 56 a compression spring 62 which when the cam lever 61 is raised forces block 42 inwardly releasing the tension on loop 59, so that when trigger block 45 has been removed the loop may be easily and quickly disengaged from the winding pins 43.

In order to hold the wire or wires when starting the loop and to properly position the lead wires for the finished loop, I have 10 designed a lead clamping trigger block B, 15 as clearly shown in Fig. 3, adapted to be mounted on one of the winding pins 43, similar to trigger block 45 heretofore described, and embodying an integral trigger mechanism 63 positioned directly under face member 64 of body portion 65. A center bore 20 66 extends through members 64, 63 and 65 adapted to receive the pin 43 when the said block is operatively positioned thereon, the 25 operation of the trigger mechanism being similar to trigger blocks 45.

The reduced end of body portion 65 is formed with an integral clamping or vice jaw 67 and is transversely or interiorly recessed, one side of which is closed by the 30 detachable plate 68, the said plate and the opposite side being apertured to receive the adjusting screw 69 provided with operating knob 70. Mounted on said screw 69 within the said opening or recess is the flanged nut 35 71 adapted to engage both sides of the adjustable clamping plate 72 slotted as at 73 and provided with handle 74 by which it may be adjusted vertically. The nut 71 is internally threaded to engage the threads 75 40 of the screw 69, so that by actuation of the said screw the plate 72 will move towards or away from the jaw 67, gripping or releasing the lead wire or wires 59' as desired.

The other end of body portion 65 is 45 constructed with a substantially yoke-shaped member 76 hinged to said body portion as at 77 and carrying screw 78 provided at its outer end with hand wheel 79 and its inner end with clamp plate 80, the said yoke member 50 76 being locked in operative position by lock-pin 81 extending through the body portion 65 and contacting with the under surface of the free end of the said yoke member as at 82, the said screw 81 carrying coil 55 spring 83 adapted to hold the said pin in locked position when the yoke member 76 has been brought to operative position and the plate 80 into clamping contact with the lead wires 59', as clearly shown in Fig. 10 60 of the drawings.

With the types of winding heads heretofore employed it has been necessary when 65 commencing a loop to fasten the end of the wire to some part of the mechanism which had to be straightened and positioned to

provide a correct lead, with a consequent loss of time and material which difficulties were materially increased when a plurality of wires were simultaneously wound, and it was to overcome such deficiencies that I designed the starting lead wire clamping mechanism above described. 70

From the foregoing it is apparent that I have designed a coil or loop winding machine embodying many novel features in 75 advance of those now in use, of great adaptability, simple in construction, efficient for the purposes intended, and the operation of which it is thought is sufficiently clear from the above description to render further explanation unnecessary. 80

Although in the foregoing, certain elements have been set forth as best adapted to perform the functions allotted to them, nevertheless, it is to be understood that various minor changes as to form, substance, etc., may be resorted to within the scope of the appended claims without departing from or sacrificing any of the principles of this invention. 85

Having thus described my invention, and without enumerating variations and equivalents, what I desire protected by Letters Patent is as set forth in the following claims: 90

1. A winding machine, the combination with a rotary head bar; of relatively adjustable loop engaging means thereon for effecting loops of varied lengths, means for securing the loop engaging means at any desired 100 position on said head bar, and cam means for effecting the longitudinal adjustment on said head bar of one of the loop engaging means with respect to its securing means.

2. A winding machine, the combination with a rotary head bar; of relatively adjustable loop engaging means thereon for effecting loops of varied lengths, means for securing the loop engaging means at any desired 105 position on said head bar, and cam means associated with one of the securing means for effecting adjustment of one of the loop engaging means with respect thereto, to effect a tightening or loosening of the loop. 110

3. A winding machine, the combination with a rotary head, of means relatively thereon for effecting loops of varied lengths including loop engaging pins, and trigger means detachably associated with said pins for effecting removal of the loop therefrom. 115

4. A winding machine, the combination with a rotary head; of means relatively adjustable thereon for effecting loops of varied lengths including loop engaging pins, a loop retaining trigger block carried by each of the said pins and including a trigger means for effecting its detachment therefrom. 120

5. A winding machine, the combination with a rotary head bar; of means relatively adjustable thereon for effecting loops of 130

1 varied lengths including loop engaging pins, trigger means detachably associated with said pins for effecting removal of the loop therefrom, one of said detachable trigger means including means for holding the starting or lead wires of the loop.

6. A winding machine, the combination with a rotary head bar; of means relatively adjustable thereon for effecting loops of varied lengths including loop engaging pins, trigger means detachably associated with said pins for effecting removal of the loop therefrom, one of said detachable trigger means including adjustable clamping means for holding the starting lead wire or wires of the loop.

7. A winding machine, the combination with a rotary head bar, winding pin blocks adjustable on said bar, a loop engaging pin carried by each block, each pin having a guide block for regulating the thickness of the loop adjustable thereon adjacent said pin blocks, and loop retaining detachable trigger blocks carried by the free ends of said pins, said pin blocks having associated clamp members for securing said blocks on said bar at any desired points thereon.

8. A winding machine, the combination with a rotary head bar including winding pin blocks slidably adjustable on said bar, a loop engaging pin carried by each block, means carried by each pin for regulating the thickness of the loop, and loop retaining trigger blocks detachably carried by the free ends of said pins, said pin blocks having associated anchor members for securing said

blocks at any desired points thereon, means interconnecting one anchor member and its associated pin block for effecting adjustment of said pin block with respect thereto to effect tightening or loosening of the coil loop.

9. A winding machine, the combination with a rotary head, winding pin block structures including loop retaining detachable trigger blocks slidably adjustable on said bar, and additional winding pin block structures including loop retaining detachable trigger blocks rotatably carried by the first mentioned winding pin blocks for effecting loops of varied configurations.

10. A winding machine, the combination with a rotary head bar, winding pin blocks including winding pins, means carried by each pin and adjustable thereon to regulate the thickness of the coil loop, loop retaining detachable trigger blocks, and additional adjustable clamping means coacting with one of said trigger blocks to hold in a predetermined position the starting lead wire or wires of the loop.

11. A winding machine, the combination with a rotary head bar, winding pin blocks including winding pins adjustable on said bar, loop retaining trigger blocks detachably carried by said pins, and adjustable clamping means co-acting with one of said trigger blocks to hold in a predetermined position the starting lead wire or wires of the loop, said clamping means being screw controlled.

SAMUEL H. BROWNING.
